INVENTOR

George E. Twambley

UNITED STATES PATENT OFFICE.

GEORGE E. TWAMBLEY, OF SACO, MAINE.

TOE-WEIGHT.

SPECIFICATION forming part of Letters Patent No. 257,907, dated May 16, 1882.

Application filed December 5, 1881. (No model.)

To all whom it may concern:

Be it known that I, GEORGE E. TWAMBLEY, of Saco, in the county of York and State of Maine, have invented new and useful Improvements in Toe-Weights, of which the following is a specification.

My invention relates to movable toe-weight for horses, the object being to so construct the same that they may be readily attached or detached without the use of screws or bolts. I attain this object by the mechanism illustrated in the accompanying drawings, in which—

Figure 1 is a view showing my toe-weight as attached to the hoof. Fig. 2 shows a part of the shoe and the bent fork and catch-spring which I use for attaching the toe-weight proper. Fig. 3 is a vertical section through the hoof, the toe-weight, and the attaching device.

The toe-weight B, Figs. 1 and 3, may be made of any desirable shape and weight. The hoof side, being concaved to fit the hoof, is provided with a dovetail-shaped longitudinal groove, into which fits the upper part of the fastening-piece D D². This fastening-piece D D² is also provided with a longitudinal groove at D², Fig. 2, this groove D² serving to give place for the latch-spring H, Figs. 2 and 3.

D' D³ are prongs extending horizontally from the lower end of the fastening-piece D, and are to be inserted between the hoof A and shoe C. (See Fig. 3.)

C', Figs. 1, 2, and 3, is a projection arising

from the upper surface of the front part of the shoe, and has an inwardly-projecting lip, c, Figs. 2 and 3.

H, Fig. 2, is a spring having a catch at each end, (see h h').

To attach my device I first place the fastening-piece D D² in position, as indicated in Fig. 3. Then the spring H is placed on the slot D², with its lower catch, h', engaged with the lip c. Then the upper part of this spring is bent back toward the hoof and the weight B is slipped downward onto the holder D, which, being dovetail in shape, holds it from coming off laterally, while the catch h of the spring H catches it at the upper end and prevents it from slipping off in that direction.

When desirable to remove the toe-weights the upper end of the spring H may be bent back and the weight B be slipped up and off from the part D; then the spring H and the parts D are free to be removed.

I claim—

In a toe-weight, the combination of the shoe C, provided with the projection c', with the holding-piece D D², latch-spring H, and weight B, all operating together substantially as described, and for the purpose set forth.

GEORGE E. TWAMBLEY.
